UNITED STATES PATENT OFFICE.

RUDOLPH CONRADER, OF ERIE, PENNSYLVANIA.

PUMP-CONTROLLING MECHANISM.

Application filed September 12, 1923. Serial No. 662,200.

To all whom it may concern:

Be it known that I, RUDOLPH CONRADER, a citizen of the United States, residing at Erie, in the county of Erie and State of Pennsylvania, have invented new and useful Improvements in Pump-Controlling Mechanism, of which the following is a specification.

It is desirable to automatically control rotary pumps so as to maintain a desired liquid level. It is particularly desirable in pumping mines and as illustrated the invention is so applied. With a rotary pump it is necessary to prime the pump and this is usually accomplished by subjecting the pump to suction which draws into the pump a sufficient amount of liquid to start the pump. Where this is done it is desirable to prevent the liquid reaching the pump producing the suction priming effort and it is also desirable to have the sequence of operations in proper relation. In the present invention the suction pressure is utilized as a factor of control and this is related to liquid level actuated controlling devices and also may be related to a liquid pressure controlling device and a speed responsive controlling means. The invention relates to these several features as well as others which will appear from the specification and claims.

The invention is illustrated in the accompanying drawings as follows:—

Fig. 1 shows a diagrammatical view of the apparatus.

Fig. 2 a sectional view of the speed responsive mechanism.

Fig. 3 a main electric switch actuating motor.

Fig. 4 a side elevation, partly in section, of the liquid level control switches.

Fig. 5 a sectional view of a retarding restriction in one of the controlling conduits.

Fig. 6 is a sectional view of a float-controlled closure for the suction line.

Fig. 7 a section on the line 7—7 in Fig. 6.

Fig. 8 a sectional view of a switch controlling mechanism subjected to suction effort and liquid pressure effort.

1 marks a mine sump, 2 a centrifugal pump which as shown is a two stage pump, 3 the intake to the pump, 4 the discharge leading from the pump, 5 the intake pipe leading from the sump to the intake 3, 6 a check valve in the discharge 4, 7 a rotor shaft for the pump, 8 a main electric motor

driving the pump, 9 an air pump for creating suction, 10 an auxiliary motor driving the air pump, and 11 a connecting pipe leading from the suction pump to the centrifugal pump. So far these parts may be of ordinary construction.

A float 12 follows the liquid level in the sump. It is slidably mounted on a rod 13 and engages shoulders 14 at the maximum and minimum levels between which it is desired to control the liquid level at X. A shoulder 15 is arranged on the rod 13 and engages a switch lever 16, the rod 13 extending through this lever. The lever 16 is pivoted at 17 on a piston 18. The outer end of the lever 16 engages a bell crank switch lever 19 pivoted at 20 and mounted on a bracket 21. The bell crank lever 19 carries the contact points 22 which as the lever is swung engage points 23, thus completing a switch in the circuit controlling the auxiliary motor 10. Line wires 24, 25 and 26 are provided in the usual manner and a wire 27 extends from the line 26 and is controlled by the switch having the contacts 22 and 23. The wire 27 leads to the auxiliary motor 10 and a wire 28 leads from the auxiliary motor to the line wire 25 of the supply line. It will readily be seen that as the liquid level X rises to the predetermined point the float 12, through the lever 16 and lever 19, will close the contacts 22 and 23 thereby completing the circuit in the line 27 and starting the motor 10.

Arranged in the line between the pipe 11 and the pump 2 is a float chamber 29 and this is connected by branch pipes 30 and 31 with the two chambers of the pump 2, a check valve 32 being provided in the branch 30 or low pressure side to prevent a disturbance in the action of the pump 2 after priming.

A float 33 is arranged in the float chamber 29. A valve 34 operates against a seat 35, the valve being guided by a stem 36 operating through a spider 37. The float 33 is made of glass to prevent corrosion and the weight of the float when the chamber 29 is free from liquid is sufficient to hold the valve 34 off its seat. When the suction pump 9 is started with the system free from liquid the suction effort is delivered through the float chamber 29 to the centrifugal pump chambers drawing the liquid from the sump to the pump 2, the check valve 6 preventing

a back-flow of air or liquid through the discharge. When the liquid reaches the float chamber it operates on the float. As the float rises the stem 36 is released from the pressure of the float and a spring 38 operating against a collar 39 at its upper end and against the spider 37 at its lower end, closes the valve 34, thus preventing the liquid from reaching the suction pump. 5 After the pump 2 is started the valve 34 is subjected to pressure and maintains it in place, thus forming a closure during the normal operation of the pump. If there is any leakage past the valve 34 into the float chamber 29 it is discharged by way of the pipe 40, this pipe being provided with a check valve 41 nearly balanced so as to discharge any liquid that may leak through the valve 34 and yet be instantly closed as 10 against any inlet of air through the suction effort.

A pipe 42 extends from the pipe 11 to a cylinder 43, this cylinder having an inlet opening 44 from which the ports 45 and 25 46 lead to the cylinder. A discharge passage 47 is connected by a port 48 with the cylinder, and the cylinder is connected by a port 49 with the atmosphere. A plunger valve 50 operates in the cylinder. This has 30 the annular way 51 around it and the valve is held normally in its upper position by a spring 52. The spring 52 is of sufficient strength to prevent the movement of the plunger 50 prior to the closing of the valve 34—in other words, the suction effort is relieved by the lifting of the liquid into the centrifugal pump and its passages and it is only after the closing of the valve 34 and the added suction effort caused there 35 40 that the plunger 50 moves. In order to adjust the tension on the spring 52 to the desired suction effort necessary to lift the liquid into the centrifugal pump and its passage an adjusting screw 53 is provided. 45 This is locked in position by a nut 54. When the plunger 50 has been subjected to the predetermined suction effort through its connection by way of the ports 45—46 it immediately moves downwardly connecting 50 the port 45 with the port 48 and closing off the port 49. The suction then is communicated to the passage 47.

A rod 55 extends upwardly from the plunger 50 and is provided with a slot 56 55 through which a switch lever 57 extends. The switch lever is pivoted at 58 on a bracket 59 and has the contacts 60 adapted to engage switch contacts 61. A spring 62 normally holds the contacts 60 and 61 in open position. When the plunger 50 moves downwardly due to the suction effort below it the rod 55 moves downwardly with it and draws the lever 57 down so as to close the contact 60 and 61. It will readily be 60 seen, therefore, that as the suction effort

moves the plunger 50, the contacts 60 and 61 are closed.

A pipe 63 leads from the discharge passage 47 to a pipe 64 which is connected to a cylinder 65 by a port 66. A valve 70 plunger 67 is mounted in the cylinder. This plunger is normally held to the left by a spring 68. It has two annular ways 69—70. The way 69 connects the port 66 with a port 71 leading to a passage 72 connected with a 75 pipe 73. The pipe 73 leads to a cylinder 74 in which there is a plunger or piston 75. A rod 76 leads from the piston 75 to a control arm 77 of a starting switch mechanism 78, the control arm being shown in Fig. 3 in neutral position and adapted to be placed at normal starting position at 79 and at normal running position at 80, the detail mechanism of the switch 78 not being shown but being of the usual construction 85 for alternating motors. Wires 81, 82 and 83 lead from the line wires 24, 25 and 26 to the switch 78 and from the switch to the main motor 8. It will be seen, therefore, that as soon as the suction effort has moved the plunger 50 and air is passed through the pipe 63 and by the way 69 of the plunger 68 to the pipe 73, the piston 75 is drawn forward through the reduction in pressure in front of the piston throwing the arm 77 95 to the starting position 79, thereby starting the main motor 8 and the pump 2.

As soon as the pump 2 is started and creates liquid pressure it is desirable to lock the switch contacts 60—61 in closed position 100 so that the priming motor or suction pump may be stopped. To this end a pipe 84 leads from the branch 31 at the pump 2 to a cylinder 85. A piston 86 is arranged in the cylinder 85. A rod 87 extends downwardly 105 from the piston 86 and has the slot 88 through which the switch lever 57 extends. This slot permits the moving downwardly of the lever through the action of the plunger 50 but after a liquid pressure is created 110 the piston 86 is forced downwardly thus locking the lever 57 in its lower position even though the plunger 50 returns to its normal or upper position, the slot 56 permitting the upward movement of the plunger 50 with the lever 57 held in its lower position by the rod 87.

After the driving motor 8 is started and reaches a pre-determined speed it is desirable to throw the control arm 77 of the switch 120 78 from the starting position at 79 to its normal running position at 80. This should only be done after the motor 8 has reached its pre-determined or desired speed. This is accomplished in the present structure as 125 follows:—A pulley 89 is fixed on an extension of the shaft 7. A belt 90 extends from the pulley 89 to a pulley 91 on a speed sensitive device. The pulley 91 is keyed on a sleeve 91^a journaled in a bracket 92. Gov- 130

erning weights 93 are pivoted on a head 91^b on the end of the sleeve 91^a. The weights are connected with a cross head 94^c on a stem 94 by links 94^b. A spring 94^c forms a centripetal element opposing the centrifugal force of the weights 93. As the speed builds up and the weights open acting through the linkage the stem 94 is operated and this contacts a push rod 95 which operates on a valve 96 in the cylinder 65. Ports 97 connect the inlet opening 64 with a chamber 98 and the chamber 98 communicates with the cylinder 65 when the valve 96 is opened. As soon, therefore, as the valve 96 is opened through the action of the speed sensitive device the plunger 67 is subjected to the suction effort and is immediately moved to the right, opening the port 71 to the atmosphere and connecting the port 66 with the port 99. The cylinder is connected through the port 99 with a pipe 100. The pipe 100 leads to the cylinder 74 at the opposite side of the piston 75 from the pipe 73. As soon as the suction effort is cut off from the left of the piston 75 and acts from the right of the piston 75, the piston immediately moves to the right carrying with it the control arm 77 and throwing the switch 78 to the normal running position. The control arm 77 is locked or held in normal running position by the usual magnet 101 operating through the linkage 102 (not shown).

After the motor 8 has been brought to its desired speed and the control switch 78 has been shifted to its normal running position it is desirable to stop the suction pump 9. This is accomplished as follows:—A pipe 103 connects the pipe 100 with a cylinder 104. The piston 18 is arranged in the cylinder 104 and when the pipe 100 is connected with the suction effort of the priming pump 9 in the manner above described the cylinder 104 is also connected and the piston 18 is drawn to the left, thus disengaging the lever 16 from the bell crank lever 19 and permitting the switch contacts 22—23 to separate through the action of the spring 105 operating on the lever 19. The lever 16 has a yielding end 106 slidingly mounted in the end of the lever and retained normally in its outer position by a spring 107. This permits the dropping of the lever 16 past the lever 19 as the shoulder 15 is lowered with the lowering of the liquid level. It will readily be seen, therefore, that as the suction effort moves the piston 18 to the left disengaging the levers 16 and 19 that the switch contacts 22—23 are opened breaking the circuit in the line 27 and stopping the motor 10 and suction pump 9. Immediately the switch contacts 22—23 are opened the suction pump 9 stops and the suction effort is, therefore, relieved throughout the mechanism. As a result of this the plunger 50 returns to its original position

as shown in Fig. 8. The plunger 68 also returns to its normal position connecting the port 99 with a port 99^a leading to the atmosphere. The switch 78 remains in normal running position due to the usual magnet 101 and linkage 102. The piston 18 returns to its normal position carrying the lever 16 into position to engage the lever 19 when the liquid level rises to the predetermined point. In order to retard the breaking of the switch contacts 22—23 controlling the suction pump 9 slightly until the operating arm 77 of the main control switch 78 has been thrown to place the switch 78 in normal running position a restriction 108 is arranged in the pipe 103 so that there is ample time for the throwing of the switch arm 77 prior to the breaking of the connection 22—23.

With the parts as now indicated the pump 2 continues to act until the water level X reaches the predetermined low level when the float 12 engages the lower shoulder 14. At this point the rod 13 is drawn downwardly and the shoulder 109 contacts a switch lever 110. The switch lever 110 has the contacts 111 adapted to engage contacts 112. This switch lever is pivotally mounted on a bracket 113 and is normally held in closed position by a spring 114. It will be seen, therefore, that as the float 12 engages the lower shoulder 14 carrying the rod 13 downwardly the shoulder 109 operating on the lever 110 opens the contacts 111—112 stopping the main motor 8 and the pump 2 as will be hereinafter explained. Immediately the contacts 111—112 are opened and the main motor 2 stops the weights 93 of the speed sensitive device assume their normal position drawing the stem 94 to the right and allowing the valve 96 to close through the action of the spring 68. The release of the liquid pressure on the connection 84 permits the piston 86 to return to its upper position and, therefore, opening the contacts 60—61. The withdrawal of pressure under the valve 34 permits the float 12 to fall as the liquid of the pump 2 returns down the inlet pipe 5. A small vent 29^a is provided leading to the float chamber 29 permitting it to receive atmospheric pressure as soon as the suction pump 9 stops. This vent is so small as not to interfere with the ordinary suction effort and provides a simple manner of restoring the pressure in this line. Thus all parts are brought to the initial position and ready for a subsequent operation when the liquid level again rises.

It is also desirable in pumps of this type that some means be provided to stop the motor 8 and pump 2 should the pump 2 lose its supply of liquid, or as is more commonly termed its "suction," such as might happen from a leak or break in the supply pipe 5 or intake 3. This safety means is provided in

the present structure through the cylinder 85. Should the pump 2 lose its liquid supply for any reason and cease to force a liquid pressure on the piston 86 the piston would 5 be moved upwardly by the spring 115. In order that the piston 86 may move upwardly at a desired pre-determined pressure the spring 115 is tensioned by an adjusting screw 116 which is locked in position by a 10 nut 116^a. The magnet 101 which holds the control arm 77 in normal running position is wired in series with the switch having contacts 60—61 and with the switch having contacts 111—112 through the shunt wire 117. It will readily be seen, therefore, that as the contacts 60—61 are opened due to the action of the spring 115 against the piston 86, rod 87 and lever 57 that the circuit in the shunt line 117 is broken thereby de- 20 energizing the magnet 101 and allowing the control arm 77 to swing to neutral position due to the action of the spring 118 as shown in Fig. 3. The contacts 111—112 are nor- 25 mally held in closed position by the spring 114. When the float is lowered by the water level X the shoulder 109 engaging the lever 110 opens the contacts 111—112 thereby breaking the circuit in the line 117 in which the magnet 101 is wired allowing the spring 30 118 to throw the control arm 77 into neutral position and stopping the main motor 8 and centrifugal pump 2.

While I have shown the apparatus as exhausting the liquid from a sump and the 35 pump here starts on a high level of liquid it will readily be understood that this condition may be reversed where it is desired to deliver the liquid to a reservoir and maintain the desired level in the reservoir.

40 What I claim as new is:—

1. In a pump controlling mechanism, the combination of a rotary pump; a motor driving said pump; mechanism controlling said motor; a suction priming means connected to the rotary pump; and means actuated by the suction pressure controlling said mechanism.

2. In a pump controlling mechanism, the combination of a rotary pump; a motor 50 driving said pump; mechanism controlling said motor; a suction priming means connected to the rotary pump; devices for closing the connection at the completion of the priming of the rotary pump; and means 55 actuated by the suction pressure controlling said mechanism to start the motor after the connection is closed.

3. In a pump controlling mechanism, the combination of a rotary pump; a motor 60 driving said pump; mechanism controlling said motor; a suction priming means connected to the rotary pump; devices closing the connection at the completion of the priming of the rotary pump comprising a 65 float-controlled valve; and means actuated

by the suction pressure controlling said mechanism.

4. In a pump controlling mechanism, the combination of a rotary pump; a suction priming pump connected to the rotary 70 pump; and controlling mechanisms for said pumps comprising means actuated by the suction pressure of the suction pump starting the rotary pump.

5. In a pump controlling mechanism, the 75 combination of a rotary pump; a suction priming pump connected to the rotary pump; and controlling mechanisms for said pumps comprising means actuated by the suction pressure of the suction pump starting 80 the rotary pump and stopping the suction pump.

6. In a pump controlling mechanism, the combination of a rotary pump; a suction 85 priming pump connected to the rotary pump; and controlling mechanisms for said pumps comprising means actuated by a liquid level starting the suction pump and actuated by suction pressure from the suction pump to start the rotary pump. 90

7. In a pump controlling mechanism, the combination of a rotary pump; a suction priming pump connected to the rotary pump; and controlling mechanisms for said pumps comprising means actuated by a liquid level starting the suction pump and actuated by suction pressure from the suction pump to start the rotary pump and stop the suction pump. 95

8. In a pump controlling mechanism, the combination of a rotary pump; a suction priming pump connected to the rotary pump; and controlling mechanisms for said pumps comprising means actuated by a liquid level starting the suction pump and actuated by suction pressure from the suction pump to start the rotary pump and actuated by a liquid level stopping the rotary pump. 100

9. In a pump controlling mechanism, the combination of a rotary pump; a suction priming pump connected to the rotary pump; and controlling mechanisms for said pumps comprising means actuated by a liquid level starting the suction pump and actuated by suction pressure from the suction pump to start the rotary pump and stop the suction pump and actuated by a liquid level stopping the rotary pump. 110

10. In a pump controlling mechanism, the combination of a rotary pump; a suction priming pump connected to the rotary pump; and controlling mechanisms for said pumps comprising means actuated by the suction pressure of the suction pump starting the rotary pump and stopping the suction pump, the means stopping the suction pump being speed responsive to the rotary pump. 115

11. In a pump controlling mechanism, 120

the combination of a rotary pump; a motor driving said pump; mechanism controlling said motor, said mechanism having a starting normal running position; a suction priming pump connected to the rotary pump; and fluid pressure actuated means controlling said mechanism.

12. In a pump controlling mechanism, the combination of a rotary pump; a motor driving said pump; mechanism controlling said motor, said mechanism having a starting normal running position; a suction priming pump connected to the rotary pump; and fluid pressure actuated means responsive to the action of the suction pump controlling said mechanism.

13. In a pump controlling mechanism, the combination of a rotary pump; a motor driving said pump; mechanism controlling said motor; fluid pressure actuated means controlling said mechanism; a suction priming pump connected to the rotary pump; and controlling devices starting the suction pump acting through said means starting the rotary pump and then stopping the suction pump.

14. In a pump controlling mechanism, the combination of a rotary pump; a motor driving said pump; mechanism controlling said motor; fluid pressure actuated means controlling said mechanism; a suction priming pump connected to the rotary pump; and controlling devices starting the suction pump acting through said means starting the rotary pump and then stopping the suction pump, said devices comprising mechanism responsive to the speed of the rotary pump.

15. In a pump controlling mechanism, the combination of a rotary pump; a suction priming pump; and controlling mechanism comprising devices responsive to the speed of the rotary pump stopping the suction pump.

16. In a pump controlling mechanism, the combination of a rotary pump; a suction priming pump; and controlling mechanism comprising a liquid level device for starting the priming pump, a fluid actuated device responsive to suction effort of the suction pump starting the rotary pump, and speed responsive devices responsive to the speed of the rotary pump stopping the suction pump.

17. In a pump controlling mechanism, the combination of a rotary pump; a suction priming pump; and controlling mechanism comprising a liquid level device for starting the priming pump, a fluid actuated device responsive to suction effort of the suction pump starting the rotary pump, speed responsive devices responsive to the speed of the rotary pump stopping the suction pump, and liquid level actuated devices stopping the rotary pump.

18. In a pump controlling mechanism, the

combination of a rotary pump; a suction priming pump; and controlling mechanism comprising a liquid level device for starting the priming pump, a fluid actuated device responsive to suction effort of the suction pump starting the rotary pump, speed responsive devices responsive to the speed of the rotary pump stopping the suction pump, and a pumped liquid pressure actuated device for stopping the rotary pump.

19. In a pump controlling mechanism, the combination of a rotary pump; a suction priming pump; and controlling mechanism comprising a liquid level device for starting the priming pump, a fluid actuated device responsive to suction effort of the suction pump starting the rotary pump, speed responsive devices responsive to the speed of the rotary pump stopping the suction pump, and liquid level and pumped liquid pressure devices stopping the rotary pump.

20. In a pump controlling mechanism, the combination of a rotary pump; a main electric motor driving said pump; a suction priming pump connected to the rotary pump; an auxiliary electric motor driving the suction pump; a liquid level controlled circuit for the auxiliary motor; a secondary circuit for the main motor; and devices controlling the secondary circuit controlled by fluid pressure from said pumps.

21. In a pump controlling mechanism, the combination of a rotary pump; a main electric motor driving said pump; a suction priming pump connected to the rotary pump; an auxiliary electric motor driving the suction pump; a liquid level controlled circuit for the auxiliary motor; a secondary circuit for the main motor; and devices controlling the secondary circuit controlled by suction pressure from the suction pump.

22. In a pump controlling mechanism, the combination of a rotary pump; a main electric motor driving said pump; a suction priming pump connected to the rotary pump; an auxiliary electric motor driving the suction pump; a liquid level controlled circuit for the auxiliary motor starting said motor; a secondary circuit for the main motor; fluid actuated devices from the pumps controlling said secondary circuit; and a liquid level device opening said circuit to stop the main motor.

23. In a rotary pump, the combination of a main electric motor driving said pump; a suction priming pump connected to the rotary pump; an auxiliary electric motor driving the suction pump; a liquid level controlled circuit for the auxiliary motor; a secondary circuit for the main motor; a switch having a starting and normal running position for the main motor; and fluid actuated means controlled by said pumps for actuating said switch to start the main motor in sequence with the auxiliary motor.

24. In a rotary pump, the combination of a main electric motor driving said pump; a suction priming pump connected to the rotary pump; an auxiliary electric motor driving the suction pump; a liquid level controlled circuit for the auxiliary motor; means for closing the connection between the priming pump and the rotary pump; a secondary circuit for the main motor; a switch controlling the secondary circuit; and fluid actuated means controlling the switch to start the main motor for closing the connection. 70
25. In a rotary pump, the combination of a main electric motor driving said pump; a suction priming pump connected to the rotary pump; an auxiliary electric motor driving the suction pump; a liquid level controlled circuit for the auxiliary motor; means for closing the connection between the priming pump and the rotary pump; a secondary circuit for the main motor; a switch controlling the secondary circuit; and fluid actuated means controlling the switch to start the main motor for closing the connection, comprising speed responsive mechanism responsive to the speed of the rotary pump. 75
26. In a pump controlling mechanism, the combination of a rotary pump; a suction priming pump; a main motor driving the rotary pump; an auxiliary motor driving the suction pump; an auxiliary circuit for the auxiliary motor; an auxiliary circuit switch controlling said circuit; a float device closing said switch; and a pressure-actuated device for opening said switch. 80
27. In a pump controlling mechanism, the combination of a rotary pump; a suction priming pump; a main motor driving the rotary pump; an auxiliary motor driving the suction pump; an auxiliary circuit for the auxiliary motor; an auxiliary circuit switch controlling said circuit; a float device closing said switch; and a pressure-actuated device for opening said switch, said pressure actuated device being subjected to the suction effort of the suction motor. 85
28. In a pump controlling mechanism, the combination of a rotary pump; a suction priming pump; a main motor driving the rotary pump; an auxiliary motor driving the suction pump; an auxiliary circuit for the auxiliary motor; an auxiliary circuit switch controlling said circuit; a float device closing said switch; and a pressure-actuated device for opening said switch, said pressure actuated device being subjected to the suction effort of the suction motor and comprising engaging levers, one of which is mounted on the movable element of the device subjected to the suction effort for breaking and closing the engagement of the levers. 90
29. In a pump controlling mechanism, the combination of a rotary pump; a suction pump; a motor driving the rotary pump; a circuit controlling the motor; a switch in the circuit; a pressure device actuated by the suction effort of the suction pump closing the switch; and a pressure device responsive to liquid pressure of pumped liquid acting on the switch, said devices being operative independently to close the switch. 95
30. In a pump controlling mechanism, the combination of a rotary pump; a suction pump; a motor driving the rotary pump; a circuit controlling the motor; a switch in the circuit; a pressure device actuated by the suction effort of the suction pump closing the switch; a pressure device responsive to liquid pressure of pumped liquid acting on the switch, said devices being operative independently to close the switch; and means for relieving the suction effort actuated device after the priming action. 100
31. In a pump controlling mechanism, the combination of a rotary pump; a motor driving said pump; a circuit controlling the motor; and devices for opening the circuit comprising a liquid level actuated mechanism and a pumped liquid pressure actuated mechanism whereby said motor is stopped either by a pre-determined level of liquid or a breaking of the liquid column leading to the pump. 105
32. In a pump controlling mechanism, the combination of a main pump; a motor driving said pump; starting mechanism for said pump; and an auxiliary pump controlling said starting mechanism. 110
33. In a pump controlling mechanism, the combination of a main pump; a motor driving said pump; starting mechanism for said pump; an auxiliary pump controlling said starting mechanism; and liquid level controlled means controlling the auxiliary pump. 115
34. In a pump controlling mechanism, the combination of a main pump; a motor driving said pump; starting mechanism for said pump; an auxiliary pump controlling said starting mechanism; and means responsive to the action of the main pump stopping the auxiliary pump. 120
35. In a pump controlling mechanism, the combination of a main pump; a motor driving said pump; starting mechanism for said pump; an auxiliary pump controlling said starting mechanism; and means responsive to the action of the main pump stopping the auxiliary pump, said means comprising devices responsive to the speed of the main pump. 125
36. In a pump controlling mechanism, the combination of a main pump; a motor driving said pump; starting mechanism for said pump; an auxiliary pump controlling said starting mechanism; and means controlled 130

by the pumped fluid from the main pump stopping the auxiliary pump.

37. In a pump controlling mechanism, the combination of a main pump; a motor driving said pump; starting mechanism for said pump; an auxiliary pump controlling said starting mechanism; and means responsive to conditions of the main pump and actuated by pressure from the auxiliary pump 10 stopping the auxiliary pump.

38. In a pump controlling mechanism, the combination of a main pump; a motor driving said pump; means for supplying fluid under pressure; mechanism controlling said 15 pump; and fluid pressure actuated devices supplied from said means controlling said mechanism.

39. In a pump controlling mechanism, the combination of a main pump; a motor driving said pump; an auxiliary pump; mechanism controlling said motor; and devices actuated by the pumped fluid of the auxiliary pump actuating said mechanism.

40. In a pump controlling mechanism, the combination of a main pump; a motor driving said pump; an auxiliary pump; mechanism controlling said motor; and devices actuated by the pumped fluid of the auxiliary pump actuating said mechanism, said 30 devices comprising means responsive to the speed of the main pump.

41. In a pump controlling mechanism, the combination of a main pump; a motor driving said pump; mechanism controlling said 35 motor; fluid actuated means controlling said mechanism; an auxiliary pump supplying said fluid; and controlling devices starting the auxiliary pump and acting through said

means starting the motor and then stopping the auxiliary pump.

42. In a pump controlling mechanism, the combination of a main pump; a motor driving said pump; mechanism controlling said motor; fluid actuated means controlling said mechanism; an auxiliary pump supplying said fluid; and controlling devices starting the auxiliary pump and acting through said means starting the motor and then stopping the auxiliary pump, said devices comprising mechanism responsive to 50 the speed of the main pump.

43. In a pump controlling mechanism, the combination of a main pump; a motor driving said pump; mechanism controlling said motor; fluid actuated means controlling said mechanism; an auxiliary pump supplying said fluid; and controlling devices starting the auxiliary pump and acting through said means starting the motor and then stopping the auxiliary pump, said devices comprising 55 mechanism responsive to liquid levels.

44. In a pump controlling mechanism, the combination of a main pump; a motor driving said pump; mechanism controlling said motor; fluid actuated means controlling said mechanism, an auxiliary pump supplying said fluid; and controlling devices starting the auxiliary pump and acting through said means starting the motor and then stopping the auxiliary pump, said devices comprising 60 mechanism responsive to liquid levels and to the speed of the main pump.

In testimony whereof I have hereunto set my hand.

RUDOLPH CONRADER.
